US0D1057124S

(12) **United States Design Patent** (10) **Patent No.:** **US D1,057,124 S**
(45) **Date of Patent:** **** Jan. 7, 2025**

(54) **CONVECTION HEATER**

(71) Applicant: **Shenzhen Xiaohei Technology Electronics Co., Ltd.**, Shenzhen (CN)

(72) Inventors: **Changcai Hu**, Liangshan Yi Autonomous Prefecture (CN); **Tiejun Xu**, Liling (CN)

(73) Assignee: **Shenzhen Xiaohei Technology Electronics Co., Ltd.**, Shenzhen (CN)

(**) Term: **15 Years**

(21) Appl. No.: **29/948,755**

(22) Filed: **Jun. 23, 2024**

(51) LOC (15) Cl. **23-03**

(52) U.S. Cl.

USPC **D23/335**

(58) **Field of Classification Search**

USPC D23/332, 328, 335-338, 342, 370, 382

CPC F24D 15/02; F24D 15/00; F24D 18/00

See application file for complete search history.

(57) **CLAIM**

The ornamental design for a convection heater, as shown and described.

DESCRIPTION

FIG. 1 is a front perspective view of a convection heater, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the convection heater, which form no part of the claimed design.

1 Claim, 8 Drawing Sheets
